AMMUNITION

George Norman Albree, Winchester, Mass.

Application December 9, 1946, Serial No. 715,017

2 Claims. (Cl. 102—50)

1

This invention relates to ammunition of the type in which the main charge is ignited by a primer or the like, and particularly to a round of ammunition such as is shown in my Patent No. 2,324,346, July 13, 1943 wherein the bullet or projectile is formed with a central opening in which is located a needle-like member that is movable relative to the body of the projectile from a retracted position, in which its pointed end is located within the projectile body, to an operative projected position in which such pointed end is projected beyond the nose of the projectile body. The invention has for its object to provide means whereby the needle-like member in the bullet or projectile will be moved from its retracted inoperative position toward its forward operative position by the detonation of the primer and before such detonation ignites the main charge, thereby insuring that said needle is in its operative position before motion is imparted to the projectile body.

During my early experiments with the "needle projectile" disclosed in my above-mentioned Patent #2,324,346, it was found that when the needle was used in connection with lead core bullets conventionally loaded (cal. .30-06 Govt.), some of the needles moved forward perfectly from the inoperative to the operative position when the rounds of ammunition were fired, while in other cases the needle failed to do so. This fact was proved by recovered bullets, and years later by flash photographs of such bullets leaving the barrel. It was, therefore, apparent that there was insufficient time for the needle to move even the short distance between its inoperative and its operative positions before the bullet started out of the neck of the case or shell and into the rifling of the barrel. It was also apparent that the rifling squeezed or swaged the lead core so that the needle was "frozen" against even the high pressure of the gas developed within the combustion chamber.

Two possible solutions suggested themselves; (1) free boring the barrel for a couple of inches or so (that is wiping out the rifling for that distance) which would, it was believed, allow sufficient time for the needle to move forward into its operative position before the bullet reached the rifling of the barrel; or (2) a ready and simple means of directing an initial pressure full upon the head of the needle prior to the ignition of the main charge. The primer itself could be used for this purpose if a means were provided to bring its extremely potent force directly against the head of the needle.

2

The immediate solution of the problem seemed to lie in providing a tubular member which communicated at one end with the primer pocket and extended through the main charge substantially to the rear end of the bullet, and arranging said tubular member so that the rear end of the needle was within the forward end thereof, with the result that the pressure developed by detonation of the primer would be through said tube and thus upon the needle head.

Such a tube would not only constitute a suitable means for applying the necessary pressure to the needle to move it forward prior to the ignition of the charge, but it would also serve the purpose of correctly positioning the bullet in the neck of the case or shell when the latter was being loaded, and it would further provide means for so-called "front ignition" of the charge with all its attendant advantages.

20 In the drawing:

Fig. 1 shows a round of ammunition embodying my invention with parts broken away to better illustrate the construction.

25 Fig. 2 is a fragmentary sectional view showing another embodiment of the invention.

Fig. 3 is a sectional view of a "needle projectile" showing the correct position of the needle during the flight of the projectile.

30 In the drawings 1 indicates the cartridge case or shell having the usual primer pocket 2 to receive the primer 3; 4 indicates the bullet, and 5 is the main charge of one or more kinds of propellant.

35 The bullet herein shown is of the type illustrated in my Patent #2,324,346, July 13, 1943, and is formed with an axial bore 6 in which is received a needle-like member 7, hereinafter referred to as a "needle." Such needle is movable in the bore between a normal inoperative retracted position, shown in Fig. 1, in which the point of the needle is within the bore of the projectile and the rear end of the needle projects rearwardly, to a forward operative position, shown in Fig. 3 in which the point of the needle extends forward beyond the body of the projectile.

40 To function properly, the needle should be moved from its retracted inoperative position shown in Fig. 1 to its forward operative position, shown in Fig. 3, before the bullet leaves the barrel of the gun, and to insure this result, I have provided means whereby when the primer 3 is detonated, the energy released will operate first 45 to move the needle forward toward its operative

50 55

position and subsequently to ignite the main charge 5.

For this purpose there is shown in Fig. 1 a tubular member 8 which extends from the primer pocket substantially to the base of the bullet 4, the rear end 10 of the needle when in its retracted, inoperative position, being within the tube 8.

Said rear end 10 of the needle 7 is preferably enlarged somewhat and is shown in the form of a poppet valve which is of a size to have a running fit within the tube 8. Said tube 8 is provided at its forward end with one or more openings 11 which are situated in front of the head 10 of the needle when the latter is in its retracted position.

With this construction when the primer 3 is detonated, the energy released will operate upon the head 10 of the needle and force the latter forwardly in the bullet 4 from its inoperative toward its operative position. As the needle in its motion relative to the bullet nears its operative position and the end 10 of the needle passes the openings 11, a communication will be established between the interior of the tube and chamber containing the main charge 5 so that the primer flash will ignite the charge. This construction, therefore, provides means by which when the primer 3 is detonated, the energy released thereby functions first to move the needle 7 forward toward its operative position before the charge is ignited and then to ignite the charge so that when the bullet 4 leaves the shell 1, the needle 7 is already in its operative position. In the projectile herein shown the movable needle member 7 which carries the tip of the projectile has a small mass or weight as compared with the body portion of the projectile. Said projectile therefore might be described as a two-part projectile comprising a body portion containing the major portion of the total mass thereof and a tip-carrying portion which is movable relative to the body portion lengthwise thereof and which has a small mass relative thereto.

When the primer 3 is detonated, the energy released thereby operates first to move the part of the projectile having the lesser mass (the needle 7) forward relative to the body of the projectile, which is stationary at this time, and after the part having the lesser mass has moved forwardly sufficiently to uncover the ports 11, the detonation of the primer then becomes effective to ignite the main charge 5 and thus set the body portion of the projectile in motion.

The tubular member 8 may be mounted in the shell 1 in various ways without departing from the spirit of the invention. Fig. 1 shows a case 1 having a conventional primer pocket 2 from which extends an opening 9 of a size to recess the rear end of the tube 8, which has a press fit therein, said tube being shown as extending clear to the rear end of the bullet 4.

In Fig. 2 there is shown a somewhat different construction in which the case 1A is constructed substantially as shown in my Patent #2,263,941, November 25, 1941, which has a shell designed primarily for hand loading. In adapting this type of shell to the present invention the short tubular part 16 of said patent is replaced by a long tubular member 16 (Fig. 2) which extends substantially to the base of the projectile as shown with reference to the tubular member 8 in Fig. 1, and is provided with openings as shown at 11 in Fig. 1.

The tubular element 8 or 16 serves not only as a means to insure that the needle 7 is moved forwardly before the main charge is ignited, but it may also serve as a positioning element for the bullet when the latter is inserted into the neck of the shell.

In connection with the construction shown in Fig. 2, the tubular element 16 also constitutes means for ejecting a detonated primer from the primer pocket. To do this the head 13 with the tubular element 16 is removed from the body of the shell, after which the detonated primer can be ejected from the pocket 2 by grasping the tube 16 and turning it to advance it through the head 13. Said member 16 may also be used to load a fresh primer into the primer pocket as described in said Patent #2,263,941.

A further and important advantage of the construction herein illustrated is that ignition of the main charge takes place at the forward end thereof. This method of igniting the charge has well known advantages.

I claim:

1. Ammunition comprising a shell having a propellant-receiving chamber containing a main charge, a primer, a projectile mounted in said shell and having an axial bore, a needle-like member in said bore and movable therein from a retracted inoperative position into a forward operative position in which the point of the needle-like member projects beyond the nose of the projectile, said needle-like member being provided at its rear end with a head which projects rearwardly from the projectile when said member is in its retracted position, and a tubular member communicating with the primer and extending substantially to the projectile and in the outer end of which the head of the needle-like member is received and has a running fit, said tubular member having communication with the propellant-receiving chamber in front of the head of said needle-like member when in its retracted position, whereby the gases generated by detonation of the primer act against the head of the needle-like member and move it relative to the projectile from its retracted position to its forward operative position, and thereby open said communication for ignition of the propellant.

2. Ammunition as described in claim 1 in which the front end of the tubular member engages the rear end of the projectile and is provided with openings communicating with the propellant-receiving chamber and situated in front of the rear end of the needle-like member when the latter is in its retracted position, whereby the energy released by detonation of the primer acts first on the end of the needle-like member to move it forward and then ignites the main charge through said openings.

GEORGE NORMAN ALBREE.
